[57] CLAIM

The ornamental design for a combined sectional sofa and table unit, as shown and described.

DESCRIPTION

FIG. 1 is a front perspective view of a combined sectional sofa and table unit showing my new design;

FIG. 2 is a left-front perspective view;

FIG. 3 is a left side elevational view, the table, seat and lounge section having been omitted for ease of illustration;

FIG. 4 is a right side elevational view, the table and sofa section having been omitted for ease of illustration; and,
FIG. 5 is a left side perspective view thereof.
The rear and bottom views are plain and unornamented.
